ATTORNEY.

UNITED STATES PATENT OFFICE.

HENRY MATHER, OF PHILADELPHIA, PENNSYLVANIA.

GRATE.

SPECIFICATION forming part of Letters Patent No. 233,783, dated October 26, 1880.

Application filed June 23, 1880. (No model.)

To all whom it may concern:

Be it known that I, HENRY MATHER, a citizen of the United States, residing in the city and county of Philadelphia, and State of Pennsylvania, have invented a new and useful Improvement in Grates, which improvement is fully set forth in the following specification and accompanying drawings, in which—

Figure 1 is a top or plan view of the grate embodying my invention. Figs. 2 and 3 are vertical sections at a right angle to each other.

Similar letters of reference indicate corresponding parts in the several figures.

This invention consists of a grate formed of rotary bars, each having means whereby any one of them may be locked without preventing the rotation of the others.

Referring to the drawings, A represents the bed-plate, and B the bars forming the grate, said bars consisting of flat plates slotted throughout their lengths, as at a, and having spurs or teeth a', of which those of the middle bar interlock with those of the adjacent side bars. Each bar has journals b, which are properly supported on bearings of the bed-plate, the front journals of the several bars projecting through the face-plate of the ash-pit for engagement of a crank or handle, c, whereby the bars may be rotated.

Formed with or secured to the front journal of each bar is an eye, perforated plate, or lug, C, in the present case depending from the journal, so disposed that a pin, D, passed through an opening in the front wall of the ash-pit will enter the lug of the respective bar and serve to lock the said bar, there being a pin for each lug.

It will be seen that the upper face of the grate presents a flat, broad, and uniform surface for properly supporting the fuel. A poker may be inserted in the slots a and worked the whole length thereof, in order to rake the fire, and air has full access to the same through

said slots a, and the space between the spurs or teeth a'. The fire may be shaken at the 45 sides or middle, or both, by rotating the relative bars, to accomplish which the proper pin or all of the pins D are withdrawn, thus releasing a bar or the bars, and by the application of the crank or handle c to the front journal of the desired bar, or successively to the journals of all of the bars, and reciprocating the same, the fire may be nicely shaken or raked where required, it being noticed that the bars are independent of each other. By 55 rotating either of the bars so that it assumes a vertical position, as shown by the dotted lines, Fig. 3, the fire may be quickly let down, it being noticed that large spaces exist between the bars for the dropping fuel, the lugs 60 C also acting as stops for preventing complete rotation of the bars.

I am aware that it is not new to make grates with separate sections which have small longitudinal apertures in them; also, that it is not 65 new to make grates with a stationary portion slotted nearly from end to end, and an unslotted screw-shaped portion rotating in a large central slot or opening of said fixed slotted portion; also, that it is not new to make 70 a grate all in one piece with zigzag slots; also, that it is not new to provide a grate made in one piece or in sections with a lug and a locking device whereby the entire grate is fastened at will. I do not claim any of the 75 above constructions.

What I do claim is—

Independent rotary bars B, each having a perforated lug or eye, c, in combination with locking-pins, whereby any one of said bars 8c may be locked without preventing the rotation of the others.

HENRY MATHER.
